UNITED STATES PATENT OFFICE.

HERBERT J. LA JOIE, OF ORANGE, NEW JERSEY, ASSIGNOR TO AUTOPIANO COMPANY,
A CORPORATION OF NEW YORK.

REROLL-CONTROLLING MECHANISM FOR MUSICAL INSTRUMENTS.

1,300,978.

Specification of Letters Patent.

Patented Apr. 15, 1919.

Application filed November 10, 1914. Serial No. 871,395.

To all whom it may concern:

Be it known that I, HERBERT J. LA JOIE, a citizen of the United States, residing at Orange, in the county of Essex and State of New Jersey, have invented a new and useful Reroll-Controlling Mechanism for Musical Instruments, of which the following is a specification.

Many of the ordinary musical instruments 10 played by a perforated note-sheet and apertured tracker-bar are now driven by an electric motor connected to operate the bellows and the various parts of the instrument.

The object of this present invention is to 15 control the re-rolling and stopping of the note-sheet in such an instrument.

To this end the invention consists in providing means for operating the switch which 20 controls the operation of the electric motor, which means is held out of operation by the note-sheet when it is in position. By this mechanism, just as soon as the re-rolling is substantially completed, the electric motor will be stopped.

25 Mechanism is also provided by which the re-rolling will take place as soon as the playing of the piece is completed, or the note-sheet has run far enough.

The invention is shown in the accompanying 30 drawing forming part of this application for patent in which,

Figure 1 is a diagrammatic view; and

Figs. 2 and 3 are detail views on enlarged scale, illustrating the operation.

35 Referring to the drawing and in detail, A designates the perforated note-sheet, and B the apertured tracker-bar of a musical instrument. C represents, conventionally, an electric motor, which is connected to drive 40 the instrument in any of the ways well known in this art.

The mechanism, as illustrated, has been 45 designed and applied in an automatic player-piano. The electric motor is controlled from a two-button switch D. A rod 9 is connected to one button 10 of the switch, and has a knob 11 on its end so that the operator can start the instrument.

To start the instrument in operation, the 50 operator pushes in on the knob 11.

12 represents the re-roll lever of the instrument, which is mounted on a shaft 13, which has a crank-arm 14 connected by a link 15 to the governor of the motor in the 55 ordinary way, the parts being arranged so

that when the re-roll lever is in the position shown, the note-sheet will be drawn forward over the tracker for playing, and so that when the re-roll lever 12 is thrown to the left, or to the position indicated in dotted 60 lines, the motor will be connected to re-roll the perforated note-sheet.

A control opening 16 is arranged in the tracker so as to be covered by the margin of the note-sheet when the same is in operative position. This control opening is connected by a tube 17 to control the operation of a primary valve 18, which controls the operation of a pneumatic 19. This pneumatic 19 has an arm 20, extending through a hole 70 in which is a rod 21 connected to a crank-arm 22 on shaft 13.

A collar 23 is adjustably secured on the rod 21, whereby a movement of the movable leaf of the pneumatic to the right will push 75 said rod 21 to the right. The rod 21 still can be moved to the right, independently of the pneumatic.

The note-sheet is provided with a notch or aperture 24, behind the perforations 80 which are cut in the note-sheet for the piece of music. By this means, when the note-sheet has been drawn over the tracker-bar as far as desired, and the piece of music been played, control opening 16 will be uncovered, as shown in Fig. 2, which will connect the electric motor so that the operation 85 of the same will rewind the perforated note-sheet.

Another control opening 25 is arranged 90 below the opening 16 and in position also to be covered by the note-sheet when the latter is in normal position. This control opening connects by a tube 26 to control the operation of a primary valve 27 of a pneumatic 95 28, which has an arm 29, adjustably connected to which is a rod 30 having a pad 31 for engaging the other button 32 of the switch.

By this arrangement, when the note-sheet 100 has been rewound, as shown in Fig. 3, the control opening 25 will be uncovered, which will cause the pneumatic 28 to operate and snap the switch D so as throw the motor out of operation.

105 By the mechanism described, the operator puts the note-sheet in position and starts the instrument in operation by pushing in on the knob 11. The note-sheet will now run forward and the piece of music played. 110

When the piece of music has been played, the control opening 16 will come into operation, the mechanism will be set so that the note-sheet will be rewound; and when the note-sheet has been substantially rewound, the operation of the electric motor will be stopped. This will leave the parts in position so that all the operator has to do is to take the re-rolled note-sheet out and put in 10 a new music roll or spool for the next piece.

The details herein shown and described may be greatly varied by a skilled mechanic without departing from the scope of the invention as expressed in the claim.

15 Having thus fully described my invention, what I desire to secure by Letters-Patent is:—

In a musical instrument, the combination of a tracker bar having a row of control 20 apertures and two openings at one end of

said control apertures, said two openings being substantially in alinement with each other transversely to the direction of the row of control apertures and adapted to be controlled by a note sheet having a notch 25 therein near the edge thereof adapted to uncover one of said openings and having its end also shaped to uncover one of said openings during the travel of the sheet, means controlled by one of said openings for stopping the sheet, and means controlled by the other of said openings for re-rolling the sheet.

In testimony whereof I have hereunto set my hand, in the presence of two subscribing 35 witnesses.

HERBERT J. LA JOIE.
